UNITED STATES PATENT OFFICE.

WILLIAM A. HENNING, OF PHILADELPHIA, PENNSYLVANIA, ASSIGNOR TO UNDERWOOD TYPEWRITER COMPANY, OF NEW YORK, N. Y., A CORPORATION OF DELAWARE.

TYPE-WRITING MACHINE.

1,095,573.

Specification of Letters Patent. Patented May 5, 1914.

Application filed May 3, 1910. Serial No. 559,154.

To all whom it may concern:

Be it known that I, WILLIAM A. HENNING, a citizen of the United States, residing in Philadelphia, in the county of Philadelphia and State of Pennsylvania, have invented 5 certain new and useful Improvements in Type-Writing Machines, of which the following is a specification.

This invention relates to gross line-spacing mechanisms for typewriting machines, 10 to facilitate the feeding of paper around the platen for a great distance to a predetermined point by a single operation.

It is often necessary to insert into the machine bills or other work sheets having wide 15 headings, or to leave a wide margin at the upper ends of the work sheets. To advance some bills or sheets to the paper printing point, the operator has to turn the platen 20 through perhaps a complete revolution or more, either by repeatedly operating the usual line space lever, or by turning the usual finger knobs on the platen axle. Either method necessitates the attention of the 25 operator to prevent overrunning the desired point on the paper, and requires undue expenditure of time and labor.

The main object of this invention is to improve and simplify gross line-spacing mechanisms, 30 whereby to enable the platen to be turned through more than one revolution at one operation of a handle; the throw of the platen also being capable of regulation for distances less than one complete revolution.

In carrying out this invention, a handle or 35 rotator, having a dog to engage the ratchet connected to the platen, lies normally against a fixed stop. The length of the line-spacing stroke of the platen is determined 40 by an adjustable stop. To increase the range of movement and effect a rotation of the platen equal to or greater than one complete rotation, at one stroke of the handle, said 45 adjustable stop is mounted for engagement with a circular rack which is usually fixed, but may at will be made movable about the platen axis, together with one or both of said stops. It is usually held fixed by means 50 of a bolt, which may be withdrawn to release the rack and enable it to turn about the platen axle, such rotation being suitably limited. Thus, the stroke of the handle or

driver is considerably lengthened, and the rotation of the platen correspondingly increased. 55

The herein described stop mechanism is also adapted for use with "condensed billing" machines, in which the platen remains connected to the crank during both backward and forward strokes of the latter. 60

In the accompanying drawings, Figure 1 is a perspective view, partly broken away, showing the invention applied to the platen frame of an Underwood writing machine. 65 Fig. 2 is a detail perspective view of the parts disassembled. Fig. 3 is an edge view of the invention, partly in section, showing the means to lock the rack stationary. Fig. 4 is a side view, showing the rack held stationary, and the driver arrested on its initial stroke by the adjustable stop. Fig. 5 is a similar view, showing the driver arrested on its return stroke, by the fixed stop. Fig. 6 is a side view, partly broken away, showing the rack released to rotate on the axle, the driver being part way on its initial stroke prior to completing one revolution. Fig. 7 is a side view, showing the position of the parts at the completion of the initial 80 stroke of the driver, after having made one complete revolution, the rack having been arrested by the engagement of the bolt with the rear face of the abutment. Fig. 8 is a similar view, showing the positions of the 85 parts at the arrest of the driver on its return stroke; the platen having been turned through more than one revolution, to advance the paper, and showing the rack arrested at its opposite limit of movement by 90 the engagement of the bolt with the abutment. Fig. 9 is a plan, showing the platen equipped with the usual line space mechanism and the improved gross line-spacing mechanism. 95

The usual platen 1 of an Underwood writing machine, is rotatably mounted by an axle 2 in the ends 3 of a platen frame, the ends of the axle projecting past the ends of the platen frame and having finger wheels 4 thereon by which the platen may be rotated forwardly or backwardly to an unlimited extent. The platen may also be rotated forwardly by the usual line-spacing mechanism comprising a line-spacing lever 1^a to operate a slide 2^a having a pawl 3^a, which en- 100 105

gages a line space wheel 4^a on the platen axle 2 to turn the platen 1.

The gross line-spacing mechanism is mounted on one end of the platen axle 2, and 5 comprises a toothed wheel or ratchet 5, the hub 6 of which is fixed to turn with the axle, the number of teeth on the ratchet corresponding with the number of teeth on said line-spacing wheel 4^a.

10 The wheel 5, and consequently the axle and platen, are given a gross rotation by means of a rotator 9 which, as herein shown, comprises a handle having a tooth, pawl or dog 7, which may, as an illustration, be slidably mounted in a guide slot 8 formed in the handle, which latter is mounted to turn loosely on the axle. A spring 10 encircling a stem 11 connected to the dog 7, and passing loosely through an apertured 15 guide lug 12 on the handle, urges the dog toward or into engagement with the ratchet.

When the rotator 9 is swung forwardly on its initial stroke, (in the direction of the arrow, Figs. 4, 6 and 7), the dog rides idly 20 over the teeth of the ratchet without rotating the platen, but upon the return stroke (in the direction of the arrow, Figs. 5 and 8), the tooth of the dog bites the ratchet, to turn the latter and the platen in a direction to 25 advance the paper, until the rotator, and consequently the platen, are arrested by contact with the home stop 13. The play of the lever or rotator 9 is between said stop 13 and a stop 14, the latter adjustable about a circum- 30 lar rack consisting of perforations 16 formed in a disk 15 on the platen axle, said disk being normally fixed, and said perforations corresponding to the number of teeth in the line space wheel. Said regulating stop 14, 35 against which the handle 9 impinges on its initial or idle stroke, is in the form of a lug carried by an arm 17 hung loosely on the axle, said stop containing a spring-pressed stem 18, one end of which forms a tooth 40 which is normally projected into one or another of the perforations 16, the opposite end having a button 19 by which to withdraw the stem to adjust the stop about the rack.

45 The rack 15 is preferably held stationary by a bolt 20, connecting the disk to an abutment or fixture 21. Said bolt may, if desired, be carried by the permanent stop 13, one end of said bolt passing through the disk 50 and into the abutment or fixture 21, which is rigidly connected to the platen frame by a tie rod 22, the fixture being fitted close against the rack disk 15 where it is held by a set collar 23.

55 To enable the handle to rotate the platen through one complete revolution or more, the stop-carrying disk or rack 15 is mounted to turn through substantially one revolution, it being released from the abutment by with-

disk is limited by the engagement of stop 20 with the final stop or abutment 21 in order to render the handle-arresting stops 13, 14 effective when the plate 15 is cast loose. The disk thus forms an interponent 70 between the rotator 9 and the final stop or abutment 21.

By reason of the rotation of the interponent disk 15 (when advancing the paper around the platen), the platen may be rotated a distance equal to the rotation of the disk 15 plus the distance between the fixed and adjustable stops 13, 14 carried by the disk, thus to advance the paper different distances over one complete rotation of the 80 platen according to the depth of the heading. This materially increases the capacity of the mechanism.

The bolt 20, when withdrawn to release the disk 15, is projected by its spring 20^a, 85 after the disk has been partially rotated (to clear the abutment 21) to serve as a stop to limit the rotation of the rack 15, by engaging the respective faces 24, 25 of the abutment, as the rack is turned in one direction or the other by the handle 9.

The disk 15 is shown released in Fig. 6, the combined bolt and stop 20 being shown in normal position, the handle 9 having been swung on its idle stroke from its normal position against the stop 13, to contact with the adjustable stop 14, which has previously been adjusted with reference to the depth of the heading on the paper being fed. A further swing of the handle in the direction of the arrow, Figs. 6 and 7, will operate to turn the disk 15 and with it the stop 20, about the axle, owing to the engagement of the handle with 14, until the bolt 20 has been brought from the position 105 shown in Fig. 6 to that shown in Fig. 7, at which time it contacts with the rear face 25 of the abutment which acts as a final stop to arrest the rack and terminate the idle stroke of the handle. During said idle 110 stroke, the pawl 7 rides idly over the teeth of the ratchet 5. On the return stroke, the pawl operatively engages the ratchet to turn the platen and advance the paper to the desired printing point. Thus it will be 115 seen that the handle first moves away from the adjustable stop 14 toward the fixed stop 13, which it picks up and by means of which it turns the disk 15 back to normal position, (Fig. 8), the stop bolt 20 now arresting both 120 the disk and the handle, the paper having been advanced to the desired extent.

It will be noted that the stop 14 may be adjusted relatively to its rack 15 and that there is afforded any degree of regulation 125 from one line space to nearly a complete rotation of the platen, and that by releasing the stop-carrying rack 15 from its fixture 21, so as to turn on the axle, until arrested

ture, another nearly complete rotation of the platen is obtainable, whereby to accommodate a wide range of headings.

The invention is also useful in feeding paper from rolls through the machine, as car records, for example, in which the roll comprises a number of paper sections or sheets separably connected, each sheet receiving a pre-determined line or lines of printing, after which the web is fed forwardly to bring the printing point of the next sheet to the printing line.

The service performed by the bolt 20 as a stop to arrest the turning of the rack may be otherwise effected and the location of the bolt on the disk 15 is not essential to the operation of the invention.

Any suitable pawl may be employed between the lever 9 and the ratchet 5; and either with or without the usual or known means for withdrawing the pawl at the conclusion of the return stroke of lever 9, as commonly done in the line-by-line platen-feeding mechanisms of typewriting machines.

Variations may be resorted to within the scope of the invention, and portions of the improvements may be used without others.

Having thus described my invention, I claim:

1. In a typewriting machine, the combination with a platen, of a driver comprising a handle to turn the platen through more than one revolution at a single stroke of the handle, a stop-carrier rotatable by said handle, stops on said carrier to arrest the driver at either limit of its travel, and an abutment to limit the extent of rotation of the stop-carrier.

2. In a typewriting machine, the combination with a platen, of a driver comprising a handle to turn the platen through more than one revolution, a stop-carrier movable back and forth by said handle, stops on said carrier to arrest the driver at either limit of its travel, and means to limit the extent of movement of the stop-carrier, one of said stops being adjustable along the stop-carrier to regulate the amount of rotation of the platen.

3. In a typewriting machine, the combination with a platen, of a swinging driver connected to turn the platen, a movable member provided with a rack, a combined locating and arresting device for the said member to releasably lock the latter stationary, an abutment engaged by the said device to limit the extent of rotation of the said member, a stop on the rack to arrest the driver and platen at the end of its return stroke, and a stop adjustable about the rack to arrest the driver on its initial stroke to limit the throw imparted thereby to the platen.

4. In a typewriting machine, the combination with a platen, of a platen-rotating mechanism, including a driver connected to turn the platen, a rack, a stop adjustable about the rack to arrest the driver on its initial stroke to determine the throw imparted to the platen, and a second stop on said rack to arrest the driver on its return stroke, said rack rotatable by said driver, through nearly a complete revolution to increase the throw imparted to the platen.

5. In a typewriting machine, the combination with a platen, of a platen-rotating mechanism including a driver connected to turn the platen, a movable member provided with a rack, a stop adjustable about the rack throughout substantially its entire circumference to limit the initial stroke of the driver, and determine the throw imparted thereby to the platen, a second stop on the rack to arrest the driver and the platen on the return stroke of the former, a lock to hold the rack member stationary and effective to release said member to increase the lengths of the initial and return strokes of the driver, and an abutment to limit the rotation of said member.

6. In a typewriting machine, the combination with a platen, of a platen-rotating mechanism, including a driver operatively connected with the platen to rotate the latter, a fixed stop to arrest the return stroke of the driver, a movable rack, a lock to releasably hold the rack stationary, a second stop between which and the fixed stop the driver is movable, said second stop being adjustable along the rack relatively to the fixed stop to control the amount of rotation imparted by the driver to the platen, and an abutment to arrest the movement of the rack when released.

7. In a typewriting machine, the combination with a platen, of a platen-rotating mechanism, including a driver operatively connected with the platen to rotate the latter, a movable rack, a stop adjustable along the rack to control the amount of rotation imparted to the platen, a fixed stop on the rack between which and the stop the driver plays, and means to releasably lock the rack stationary and to arrest the movement of the rack when free.

8. In a typewriting machine, the combination with a platen, of a platen-rotating mechanism, including a driver operatively connected with the platen to rotate the latter, a movable rack, a stop adjustable along the rack to control the amount of rotation imparted to the platen, a fixed stop on the rack between which and the said adjustable stop the driver plays, a locating bolt to releasably lock the rack stationary, and an abutment engaged by the bolt when the rack is free, to arrest its movement.

9. In a typewriting machine, the combination with a platen, of a platen-rotating mechanism, including a driver connected to turn the platen, a movable member provided with a rack, a stop adjustable about the rack to arrest the driver on its initial stroke to determine the throw imparted to the platen, and a second stop on said rack to arrest the driver on its return stroke, said rack rotatable by said driver, through nearly a complete revolution to increase the throw imparted to the platen.

mechanism, including a driver operatively connected with the platen to rotate the latter, a movable rack, a stop adjustable along the rack to control the amount of rotation imparted to the platen, a fixed stop on the rack between which and the said adjustable stop the driver plays, a locating bolt carried by the fixed stop and held stationary to releasably hold the rack motionless, and an abutment engaged by the bolt when the rack is released, to arrest the movement of said rack.

10. In a typewriting machine, the combination with a platen, of platen-rotating mechanism comprising a ratchet rigidly connected with the platen, a driver turning relatively to the platen and having a tooth to engage and rotate the ratchet and platen when the driver is turned in one direction and to ride idly over the ratchet when the driver is turned in the opposite direction, a fixed stop to arrest the driver when turned in one direction, a rotatable rack on which the fixed stop is mounted, a regulating stop adjustable along the rack and engaged by the driver, to control the amount of rotation of the platen, a lock to releasably hold the rack stationary, and an abutment to arrest the rack when released.

30. 11. In a typewriting machine, the combination with a platen, of platen-rotating mechanism including a reciprocatory driver mounted to turn concentrically with the platen, means forming a one-way driving connection between the driver and platen to permit the driver to turn the platen at one stroke throughout one complete revolution or more, and to move through its other stroke without turning the platen, and stops between which the driver is reciprocated, said stops mounted for a limited rotation with the driver.

12. In a typewriting machine, the combination with a platen, of platen-rotating mechanism including a reciprocatory driver having a one-way driving connection with the platen and mounted to turn concentrically with the platen and effective to turn the platen at one stroke throughout one complete revolution or more, and to move through its other stroke without turning the platen, and an adjustable stop having a limited rotation with the driver to arrest the driver to control the amount of rotation imparted to the platen.

13. In a typewriting machine, the combination with a platen, of platen-rotating mechanism effective to turn the platen throughout one complete revolution or more, and including a driver connected to turn the platen, a stop carrier movable by said driver, stops on the carrier, between which the driver swings to control the amount of rotation of the platen, one of said stops be-

of the driver, and means to arrest the movement of the stop carrier in either direction.

14. In a typewriting machine, the combination with a platen, of a platen-rotating mechanism effective to turn the platen throughout one complete revolution or more, and including a driver connected to turn the platen, a stop carrier movable by said driver, stops on the carrier, between which the driver swings to control the amount of rotation of the platen, one of said stops being adjustable to vary the length of travel of the driver, and means to releasably hold the stop carrier stationary and to arrest its movement when free.

15. The combination with a revolute platen, of a driver comprising a handle to turn the platen, a carrier, relatively adjustable stops on said carrier for limiting the stroke of the handle relatively to the carrier, said carrier movable by said handle, and means fixed relatively to the movement of the carrier to arrest said carrier when moved by the handle.

16. The combination with a revolute platen, of a driver comprising a handle to turn the platen, a carrier, relatively adjustable stops on said carrier for limiting the stroke of the handle relatively to the carrier, said carrier movable by said handle, and means fixed relatively to the movement of the carrier to arrest said carrier when moved by the handle.

17. In a typewriting machine, the combination with a revolute platen, of a driver concentric therewith and comprising a handle and effective to turn said platen so that the driver and platen move as a unit in one direction, and said driver moves idly in the opposite direction, a stop for arresting said driver in one direction, and means for arresting said driver at a predetermined point after more than a full revolution in the reverse direction.

18. In a typewriting machine, the combination with a revolute platen, of a driver concentric therewith comprising a handle and effective to turn said platen so that the driver and platen move as a unit in one direction, and said driver moves idly in the other direction, a rack loose on the axle of said platen, said driver rotatable relatively to the rack, a stop on said rack to limit the movement of said driver relatively to the rack, a fixed abutment, and a stop on said rack to collide with said fixed abutment to arrest said rack.

19. In a typewriting machine, the combination with a revolute platen, of a driver concentric therewith and effective to turn said platen, so that the driver and platen move as a unit in one direction, and said

- rack loose on the axle of said platen, a stop on said rack to limit the movement of said driver relatively to the rack in its revolution, an abutment fixed to the platen frame, 5 and a stop arranged to control the movement of said rack from said abutment and to limit the rotation of said driver.
20. The combination of a platen driver, an abutment therefor, an interponent between said driver and said abutment, releasable means for securing said interponent against movement, and a stop adjustable upon said interponent to limit the stroke of said driver; whereby, at option, the driver 15 may be arrested either at its engagement with said adjustable stop, or at the conclusion of the movement of the interponent effected by said driver through engagement with said adjustable stop.
21. The combination of a platen driver, an abutment therefor, a rotatable interponent between said driver and said abutment, releasable means for securing said interponent against rotation, a stop adjustable upon said 25 interponent, and means to secure said adjustable stop to the interponent at different adjustments, for variably limiting the stroke of the driver.
22. The combination of a platen driver, an abutment therefor, a rotatable interponent disk between said driver and said abutment, releasable means for securing said disk against rotation, an arm mounted to swing about the axis of said disk, and a stop carried upon said arm and provided with a latch or dog, said disk having perforations or seats for said latch or dog, to permit adjustment of said stop.
23. The combination of a platen driver, an abutment therefor, a fixed but releasable interponent in the form of a revoluble disk between said driver and said abutment, a stop associated with said disk, said disk having seats or perforations, and means to coöperate with said seats or perforations to permit adjustment of said stop, to vary the stroke of said driver.
24. The combination of a revoluble platen, a driver mounted to turn about the axis of the platen, a ratchet wheel and pawl to enable said driver to drive the platen in only one direction, stops for regulating the stroke of the driver, and a carrier for one of the stops, said carrier having a limited rotation 55 about the platen axis to permit the driver to have a range of movement in excess of an entire revolution of the platen.
25. The combination with a platen and a driver therefor, of means forming a one-way driving connection between the platen and driver, a stop for said driver, a rotatable member with which said stop is adjustably connected, a stationary abutment to limit the rotation of said rotatable member, and means to lock said rotatable member 65 against rotation.
26. In a typewriting machine, the combination of a platen frame, a rotary platen, an abutment adjustable relatively to the platen frame, a platen driver, an interponent, means carried thereby and coöperating with said abutment to limit the rotation of the interponent, and a stop in the path of the platen driver and adjustably connected to the interponent. 75
27. In a typewriter, the combination of a platen, a driver therefor, a rotatable interponent, a stop in the path of the driver adjustably connected to the interponent, and means to limit the rotation of the interponent in both directions, and to hold the interponent against rotation. 80
28. The combination of a platen, a platen driver, a rotatable disk, relatively adjustable stops carried by the disk and between 85 which said driver is adapted to oscillate, and means to limit the rotation of the disk, and to lock the disk against rotation.
29. In a typewriting machine, the combination of a platen axle, a platen secured thereto, a platen driver, means forming a one-way driving connection between the driver and platen, a disk rotatable on the platen axle, stops for the driver carried by said disk, one of said stops being adjustable to vary the amplitude of oscillation of the driver between the stops, a releasable device to lock the disk against rotation, and means to limit the rotation of the disk when thus released. 90 95 100
30. The combination of a platen, a platen axle, a disk rotatable on said axle, a stop carried by the disk, an arm rotatable on said axle, means for connecting said arm to the disk at different positions of rotation relative to the disk, a stop on said arm, a platen driver adapted to oscillate between said stops, means to releasably lock the disk against rotation, and means to limit the rotation of the disk when thus released. 105 110
31. The combination with a platen and a driver therefor, of means forming a one-way driving connection between the platen and driver, a rotatable member, a stop adjustably connected to said rotatable member, and engageable by said driver, a stationary abutment to limit the rotation of said rotatable member effected by said driver through said stop, and releasable means to hold said rotatable member fixed when desired. 115 120
32. The combination of a revoluble platen, a driver mounted to turn about the axis of the platen, a ratchet wheel and dog to enable said driver to drive the platen in only one direction, and means for regulating the stroke of the driver, said regulating means comprising relatively adjustable stops, cer-

tain of said stops movable with the driver a limited distance, said regulating means permitting the range of stroke of the driver to be adjusted through a series of increments 5 from a fraction of a revolution to more than an entire revolution of the platen.

33. The combination with a platen and a driver therefor, of means forming a one-way driving connection between the platen and 10 driver, a rotatable member, a stop adjust-

ably connected to said rotatable member, and engageable by said driver, and a stationary stop to limit the rotation of said rotatable member effected by said driver through said adjustable stop.
